Primary Examiner — Jennifer L Watkins*Assistant Examiner* — Samantha Lynne Brodowski(74) *Attorney, Agent, or Firm* — Fross, Zelnick, Lehrman & Zissu PC; Charles T.J. Weigell, Esq.(57) **CLAIM**

The ornamental design for a HANDBAG as shown and described.

DESCRIPTION

FIG. 1 is a front perspective view of a handbag showing my new design;

FIG. 2 is a front view thereof;

FIG. 3 is a back view thereof;

FIG. 4 is a left side view thereof;

FIG. 5 is a right side view thereof; and

FIG. 6 is a top view thereof.

The portions of the bottom of the handbag that are not visible in the various views form no part of the claimed design. The evenly dashed broken lines depict portions of the article and form no part of the claim. The dot-dash-dot broken lines depict a claim boundary. Any portion of the article outside of the claim boundary forms no part of the claimed design.
